UNITED STATES PATENT OFFICE.

JOHN C. MOELL, OF WAPAKONETA, OHIO.

TIE.

1,380,235.

Specification of Letters Patent. Patented May 31, 1921.

Application filed January 11, 1921. Serial No. 436,452.

To all whom it may concern:

Be it known that I, JOHN C. MOELL, a citizen of the United States, residing at Wapakoneta, in the county of Auglaize and 5 State of Ohio, have invented new and useful Improvements in Ties, of which the following is a specification.

My present invention has reference to railway ties and means associated therewith for 10 securing rails thereon.

The object is the production of a tie constructed of metal, concrete or other suitable material which has its upper face so shaped as to contact with one of the sides of the 15 rails and to receive wedge members which engage with the opposite sides of the rails, means being provided for locking the wedges on the tie.

A further object is the production of a 20 railway tie in which the base portion thereof is of a formation to firmly seat itself in the roadbed and hold the tie against tilting or lateral movement, and which has removable means designed to coengage with the 25 upper surface thereof for securely holding rails thereon.

The foregoing, and other objects which will appear as the nature of the invention is better understood, may be accomplished 30 by a construction, combination and operative arrangement of parts, such as are disclosed by the drawings which accompany and which form part of this application.

In the drawings:—

35 Figure 1 is a perspective view showing rails secured upon a tie constructed in accordance with this invention.

Fig. 2 is a longitudinal sectional view therethrough.

40 Fig. 3 is a sectional view approximately on the line 3—3 of Fig. 2.

Fig. 4 is a perspective view of the tie.

Fig. 5 is a similar view of one of the wedge blocks.

45 The tie 1 has its base V-shaped in cross section, and the angle sides thereof are indicated for distinction by the numeral 2. The top of the tie includes upstanding ends 3 and 4, and a central upstanding portion 5.

50 The end 4 has its lower portion notched, as at 6 to receive therein the outer flange on a rail 7. The central enlargement 5, opposite the end 3, in a like manner, has a notch 8 to receive the inner flanged portion of a 55 rail 9. The face of the enlargement 5, oppo-

site that provided with the notch 6 has an inwardly beveled downwardly inclined surface 10, and in a like manner the inner face of the end 3 has a similar surface 11. Both of these inwardly inclined downwardly extending surfaces are designed to receive thereon complementary surfaces in the nature of tongues 12 and 13 formed on the outer face of wedge blocks 15 and 16. The tongues 12 are arranged at such an angle 60 as to permit of the blocks being slid through the grooves into engagement with the faces of the rails, whereby the rail 9 will be forced against the notched wall of the block or central portion 5 of the tie, and the rail 7 in 70 a like manner, will be forced against the rail receiving end 4 of the tie. While the blocks are shown in the drawings on the same side of both rails, it is obvious that should it be found desirable, the said blocks 75 may be arranged to engage either the inner or outer sides of the rails. The wedge members have their lower edges arranged at a bevel or inclination, as indicated by the numerals 17 and 18 respectively, the said inclined surfaces contacting with the beveled upper surfaces of the rail base flanges not received in the notches.

Each of the wedge blocks has a central opening therethrough which aligns with a 80 similar opening in the body of the tie, and passing through these openings are bolts 19 that have their heads received in the V-shaped channel at the base of the tie and through shanks engaged by nuts 20 which 85 force washers 21 against the upper faces of the wedge blocks. Suitable means may be provided for locking the nuts on the bolts, and from the foregoing description, when taken in connection with the drawings, it 90 is thought that the simplicity of the construction and the advantages thereof will be 95 perfectly apparent to those skilled in the art to which such inventions relate.

Having described the invention, I claim:— 100
A rail tie comprising a body whose base is V-shaped in cross section and whose top is formed with upstanding ends and an upstanding block between the ends, and the lower wall between the upstanding portions 105 providing rail seats, one of the said ends having its inner face notched to receive the base of one of the rails, the central block having one of its ends notched to receive the base of the second rail, the opposite face 110

of the block having a V-shaped downwardly inclined groove, the inner face of the second end having a V-shaped downwardly inclined groove, wedge blocks each having one face provided with a V-shaped tongue complementary with the V-shaped grooves and designed to be received in the respective

grooves, and to have their straight faces contacting with the rails, and removable means for securing said wedge blocks on 10 the tie.

In testimony whereof I affix my signature.

JOHN C. MOELL.
